UNITED STATES PATENT OFFICE.

JOHN REDMOND, OF FAIRCHANCE, PENNSYLVANIA.

COMBINATION WHEEL AND RAIL BRAKE.

SPECIFICATION forming part of Letters Patent No. 728,130, dated May 12, 1903.

Application filed July 25, 1902. Serial No. 116,899. (No model.)

To all whom it may concern:

Be it known that I, JOHN REDMOND, a citizen of the United States of America, residing at Fairchance, in the county of Fayette and

5 State of Pennsylvania, have invented certain new and useful Improvements in Combination Wheel and Rail Brakes, of which the following is a specification, reference being had therein to the accompanying drawings.

10 This invention relates to certain new and useful improvements in car-brakes, and relates more particularly to that class of brakes which are adapted to engage both the car-wheels and the rails.

15 Further, the invention contemplates the employment of a rail-brake which is hinged to the wheel-brake, whereby as the said track-brake is lowered into engagement with the rails it will automatically force the wheel-brake into engagement with the rails.

Briefly described, my invention consists of a pair of wheel-brake shoes which are suspended from a common brake-beam and a pair of track-brake shoes hinged to the said

25 wheel-brake shoes. Connected to the wheel-brake shoes are cables. These cables have their upper ends connected to a common winding-shaft operated by a lever at the front of the car.

30 This construction will be hereinafter more specifically referred to and then particularly claimed, and in describing the invention in detail reference is had to the accompanying drawings, forming a part of this specification, and wherein like numerals of reference indicate like parts throughout the several views, in which—

Figure 1 is a view in side elevation of the front car-truck, partially in section and showing my improvement secured in position.

40 Fig. 2 is a sectional view taken on line 22 of Fig. 1. Fig. 3 is a detail view of the winding-drum lever; and Fig. 4 is a top plan view of the brake-shoes and the shaft to which the same are connected, the wheels and car-platform being removed.

45 1 indicates the wheel-brake shoes, which have their inner faces curved to conform to the curvature of the wheel's periphery and 50 their rear faces provided with an approximately U-shaped recess to receive the brake-beam 2.

3 indicates a pair of downwardly-inclined apertured lugs formed integral with the shoes 1 at a point below the brake-beam 2 and to 55 which the upwardly-extending lugs 4 of the track-shoes 5 are pivoted. These track-shoes 5 are both provided on their lower faces with flanges 6 to engage the rail-groove and have their rear ends inclined, as at 7, to conform 60 to the curvature of the outer face of the brake-shoes 1, so that when the brake is in the position shown in Fig. 1 the rear end of the said track-brake shoe will bear evenly thereagainst.

65 8 indicates cables having their lower ends secured to the brake-shoes 1 and their upper ends secured to the transversely-arranged shaft 9, journaled in the brackets 10, secured to the car-platform.

70 11 indicates a quadrant rigidly fixed on the shaft 9 and having connected thereto the cable 12, which is wound on the shaft 13, journaled in the approximately U-shaped bracket 14, secured to the forward end of the car-plate- 75 form.

15 and 16 designate ratchet-wheels secured to the shaft 13 on opposite sides of the bracket 14, which ratchet-wheels have their teeth arranged in opposite directions, as is clearly 80 shown in Figs. 1 and 3 of the drawings.

17 indicates a pawl pivoted to one arm of the bracket 14 and provided with an operating-arm extending through the opening 18 in the car-platform. This pawl engages the 85 ratchet-wheel 15 and has the upper end of its operating-arm provided with an enlarged head 19.

20 indicates the operating-lever for shaft 13 and has its lower end loosely mounted there- 90 on. 21 indicates a pawl pivotally mounted on the said lever, which pawl is operated by the link 22.

95 In operation the operating-lever 20 is oscillated, and during the forward movement thereof the pawl 21 will engage the teeth of the ratchet-wheel 16, thereby rotating the shaft 13 and winding the cable 12, and consequently elevating the brake-shoe. When it is desired to apply the brakes, the operating-arm 18 of 100 the pawl 17 is depressed, thereby throwing the pawl 17 out of engagement with the ratchet-wheel 15, whereby the shaft 13 is permitted to rotate, (the pawl 21 riding over the

teeth of its ratchet-wheel,) and the brake will be lowered by gravity into engagement with the wheels and rails, as heretofore described.

It will be noted that various changes may 5 be made in the details of construction without departing from the general spirit of my invention.

Having fully described my invention, what I claim as new, and desire to secure by Letters 10 Patent, is—

1. In a car-brake, the combination of the wheel-shoes, track-shoes pivotally secured to the said wheel-shoes, said track-shoes being adapted to engage the rails and thereby force 15 the wheel-shoes into engagement with the wheels, and means for throwing the said brake-shoes into and out of operation, substantially as described.

2. In a combined wheel and track brake, the 20 combination with the wheel-engaging shoes,

of track-engaging shoes pivotally secured to the said wheel-shoes, and having their rear ends inclined to conform to the curvature of the outer face of the said wheel-shoes, a brake-beam secured to the said wheel-shoes, means 25 for raising the said brake-shoes, means for locking said shoes in their raised position, and means for releasing the same whereby they will be lowered by gravity, said track-shoes being adapted to engage the rails where- 30 by the wheel-engaging shoes are forced into engagement with the wheel, substantially as described.

In testimony whereof I affix my signature in the presence of two witnesses.

JOHN REDMOND.
